UNITED STATES PATENT OFFICE.

FREDERICK W. COOK, OF SAN FRANCISCO, CALIFORNIA.

SAW-MILL SET-WORKS.

SPECIFICATION forming part of Letters Patent No. 398,942, dated March 5, 1889.

Application filed September 27, 1888. Serial No. 286,568. (No model.)

To all whom it may concern:

Be it known that I, FREDERICK W. COOK, of the city and county of San Francisco, State of California, have invented an Improvement 5 in Saw-Mill Set-Works; and I hereby declare the following to be a full, clear, and exact description of the same.

My invention relates to the class of saw-mill machinery, and especially to the set- 10 works by which the knees or standards are properly controlled and adjusted; and my invention consists in the novel constructions and combinations of devices, which I shall hereinafter fully describe and claim.

15 Referring to the accompanying drawings for a more complete explanation of my invention, Figure 1 is a perspective view of the saw-mill carriage having the set-works and standards or knees thereon, and showing the set- 20 works and the sliding or adjustable beveled gears. Fig. 2 is a vertical longitudinal section through the pawls and ratchets of the set-works. Fig. 3 is a cross-section through one of the ratchets and pawl-carriers of the same. 25 Fig. 4 is a longitudinal section showing the adjustable beveled gear and means for operating it. Fig. 5 is a view of the hinged limiting-plates O.

A is the frame of a saw-mill carriage. 30 B are the transverse tracks or guides on which the standards or knees C are mounted and adapted to move by the rotation of the set-screws D, all in the usual manner.

E is the set-shaft, upon which are rigidly 35 keyed or fixed the ratchets F. Loosely mounted upon the set-shaft, and between the two ratchets, are sleeves G, having at one end the pawl-carrier portion g, and upon their faces the segmental gears g'. In the carriers 40 g are fitted the pawls H, which engage the ratchets F.

I is a short cross-shaft, on the inner end of which is secured or formed a mutilated gear, J, the teeth of which are in two distinct sections, one section meshing with the segmental gear g' of one of the loose sleeves G, and the other section meshing with the segmental gear of the other loose sleeve.

K is the set-lever, the lower end of which is 50 mounted on the short cross-shaft I and bolted to the mutilated gear J, so that by vibrating the lever K is oscillated and engages

the segmental gears on each side alternately, thereby causing the pawls to operate the ratchets alternately and communicate motion 55 to the set-shaft. The lever K plays within the fixed guide L, which is a curved slotted or two-part piece or quadrant.

M is a rock-shaft journaled in the base of the fixed guide, and having a lever, N, attached. To each end of the rock-shaft is secured a curved arm, m, which bears up under the outer edges of all the pawls H, whereby when said arms are thrown upwardly by the rocking of the shaft M, actuated by the 65 lever N, said pawls are raised from their engagement with the ratchets and are thus thrown out of action when desired.

In order to define the movement or stroke of the lever for the purpose of setting the 70 knees or standards to the proper position according to the thickness of the lumber to be cut, and also to provide for the different saw-kerfs, I have the following mechanism: Lying across the top of the slotted or two-part guide 75 L are a number of independent plates, O. These plates are hinged at their back ends at o to one side of the guide, and each has a handle-piece, o', whereby it may be thrown back on its hinge so as to be removed from 80 the path of the lever. The foremost of these plates is provided with an adjustable contact-piece in the shape of a cross-bar, P, which is mounted and adapted to slide upon projecting screw-bolts p, and is adjusted to place by 85 means of the nuts p' on said bolts. By manipulating these nuts the cross-bar P may be moved either to or from the body of the plate O. At the other end of the guide, behind the lever, is a similar adjustable stop or cross- 90 bar, Q, which is mounted and adapted to slide upon fixed screw-bolts q, and is adjusted by means of nuts q'. The plates O are all proportioned so as to limit the stroke of the lever according to the thickness of the lumber in 95 inches. For example, when the lever is moved the distance between the stops Q and P, the knees or standards will be set up to position to cut a board one inch thick. Now, to cut a board two inches thick, the first plate O, with 100 its cross-stop P, is thrown backward on its hinge so as to get out of the way of the lever, leaving the second stop-plate O in position to limit the lever's movement, and this second

stop-plate is in such a position that the lever can move through a sufficient distance to set the knees or standards for a two-inch board. For a three-inch board the second stop-plate 5 O is thrown back, thus leaving the third stop-plate O to limit the lever, and so on.

The object of the adjustable stop P on the first stop-plate O is to provide for the different kerfs occasioned by different thickness of 10 saws. Thus, if a thin saw is being used, the cross-bar stop P is run out so as to sooner limit the lever, and when a thicker saw is used said stop is run back slightly to let the lever move farther forward. The object of 15 the adjustable cross-stop Q at the other end is to follow up the movement of the adjustable cross-stop P in providing for the saw-kerf, so that the stroke of the lever is still defined by the stop-plates, while its limits are 20 changed by the cross-stops. Therefore, if the cross-stop P be run out, the cross-stop Q will be run back, and vice versa.

In order to provide for the thickness of 25 boards in fractions of inches I have the holes o^2 in the guide, and the removable pin o^3 , which is adapted to pass through the holes transversely, so as to limit the lever.

On the end of each set-screw D is a bevel-gear, d, and upon the set-shaft E, near each 30 end, is a bevel-gear, R, which meshes with the gear d of the set-screw and imparts rotation to said screw. The gear R is formed or connected with a sleeve, r, Fig. 4, which is mounted upon a feather or spline, e, on the end of the 35 set-shaft, so that said sleeve, with its bevel-gear, may be moved longitudinally on the set-shaft to throw said gear into or out of engagement with the bevel-gear d. The lower portion of the sleeve r is forked or has flanges 40 r', which form a seat for the eccentric S, which plays between them, said eccentric bearing on the short shaft s, provided with a handle-lever, s', by which it is operated. Therefore by oscillating the handle-lever s' the eccentric 45 effects the longitudinal movement of the sleeve r and the gear R. The sleeve r and the eccentric are confined in a box, T, the lower portion of which is fixed; but the upper portion, t, is fitted to the lower portion 50 in such a manner that it may slide back and forth, thus accompanying the sleeve in its motion.

I am aware that the gears of the set-shaft have been mounted thereon on a feather and adapted to be thrown into and out of engagement by means of a lever and yoke. I do not, therefore, claim a sliding gear, but confine myself to the construction shown as being simple and effective.

I am aware also that in saw-mill set-works 60 ratchets upon the set-shaft, pawl-carriers having pawls engaging said ratchets, segmental gears, and an oscillating mutilated gear meshing therewith are not new, and I do not claim such, broadly; but

What I do claim as new, and desire to secure by Letters Patent, is—

1. In saw-mill set-works, the set-lever and the fixed guide by which it is directed, in combination with the independent hinged 70 limiting-plates O, secured to the guide, and the adjustable cross-stop on the foremost of said plates, substantially as herein described.

2. In saw-mill set-works, the set-lever and the fixed guide by which it is directed, in 75 combination with a series of independent hinged limiting-plates, O, secured to the guide, the adjustable cross-stop P on the foremost of said plates, and the adjustable cross-stop Q at the other end of the guide behind the lever, substantially as herein described.

3. In a saw-mill set-works, the set-shaft and the set-screw having a gear, in combination with the adjustable gear R on the set-shaft, the sliding sleeve carrying said gear, the eccentric S, seated in the base of the sleeve, and the lever s, for operating the eccentric to slide the sleeve and throw its gear into or out of engagement with the gear of the set-screw, substantially as herein described.

4. In saw-mill set-works, the set-shaft and the set screw having a gear, in combination with the sliding sleeve on the set-shaft, the gear on the sliding sleeve meshing with the gear on the set-screw, the eccentric and lever 85 for moving the sleeve, and the box T, having the sliding top t, fitted over the sleeve, substantially as herein described.

In witness whereof I have hereunto set my hand.

FREDERICK W. COOK.
